A. BURNS

AUTOMATIC MAGNETIC SEPARATOR

Filed Feb. 20, 1928

UNITED STATES PATENT OFFICE.

ARCHIE BURNS, OF DES MOINES, IOWA.

AUTOMATIC MAGNETIC SEPARATOR.

Application filed February 20, 1928. Serial No. 255,694.

The principal object of this invention is to provide a magnetic separator for removing magnetizable bodies such as nails, wire, fragments of metal and the like from granular or 5 impalpable non-magnetic material.

A still further object is to provide a magnetic separating device for arresting scraps of iron and the like that automatically prevents the metal pieces from passing on into 10 the mill or bin in the event that the magnetic separator ceases to function either by breakage or the shutting down of the power plant.

A still further object of this invention is to provide a magnetic separator that warns the 15 operator when the electro-magnets are not working or vice versa.

A still further object of this invention is to provide a magnetic separating device for 20 arresting fragments of metal or the like from grain that can automatically be cleaned of such bodies without danger of them passing on into the mill or bin merely by the shutting down of the power plant or the breaking of the circuit of the magnetic separator with the generator.

More specifically, the object of this invention is to provide an automatic magnetic separator for removing magnetic bodies from grain or the like, comprising an inclined 30 chute in which the grain travels, two metal plates in the bottom of the chute in electrical contact with an electro-magnet, and a trap door in the bottom of the chute below the metal plates, designed to be held in normal 35 closed position by the attraction of the plates and capable of falling to an open position when the electro-magnet is not functioning, thereby preventing the released metal fragments from passing on downwardly in the 40 chute.

A still further object of this invention is to provide an automatic magnet separator for removing magnetizable objects from non-magnetic material that is economical to manufacture and durable in use.

These and other objects will be apparent to those skilled in the art.

My invention consists in the construction, arrangement and combination of the various 50 parts of the device, whereby the objects contemplated are attained as hereinafter more fully set forth, pointed out in my claims and illustrated in the accompanying drawings, in which:

Fig. 1 is a side view of my device installed

and ready for use with sections cut away to more fully illustrate the same.

Fig. 2 is an enlarged top plan view of a section of the chute showing the method of holding the trap door in closed position and 60 is taken on line 2—2 of Fig. 1.

Fig. 3 is a perspective view of the electro-magnet used in the device.

Fig. 4 is a longitudinal sectional view of one of the cores of the electro-magnet taken 65 on line 4—4 of Fig. 3 and illustrates its interior construction.

Fig. 5 is an enlarged perspective view of one of the plates designed to be secured in the bottom of the chute.

70

Heretofore, much trouble has been experienced by operators of grain mills and the like by iron or metal objects passing with the grain into the grinding and pulverizing mills. This was especially true of all hammer mills 75 and when experienced, which was quite often, the mill had to be shut down and taken apart to remove the offending cause. Many mills have magnetic plates in the chute for collecting the metallic fragments before the 80 grain reaches the mill, but these devices are not entirely satisfactory because when the magnets failed or the plant was shut down accidentally or willfully, all the metal bodies collected, would be released in a group and 85 pass into the mill or grinder. I have overcome these disadvantages as will be appreciated by those familiar with the art.

I have designated the platform of the mill by the numeral 10, supported on which is the 90 hopper 11, the grain 12 or other material being fed into this hopper by the endless conveyor 13 or other suitable means. Communicating with the bottom of this hopper and leading to the mouth of the mill 14 is the 95 inclined chute 15. To prevent any foreign particles entering the mill, the shield 16 is provided, completely inclosing the mouth of the mill except the side into which the chute enters. Embedded in the bottom of the chute 100 and flush with the same as shown in Fig. 2, are the two metal plates 17 and 18. On the under side of the chute and having its two poles making contact and secured by suitable means to the two plates 17 and 18 respectively, is my electro-magnet of horseshoe construction. This electro-magnet comprises the usual base bar 19 having the two poles or cores 20 and 21 extending therefrom. Around each of these cores is a winding of 110

insulated wire 22, as shown in Fig. 4. The numeral 23 designates washers preferably of insulating material on each side of each of the coils of wire 22. The numeral 24 designates 5 insulating protective cord around each of the coils. Secured to the shaft 25 of the mill 14 is the pulley wheel 26. Embracing this pulley wheel and the pulley wheel 27 of the generator 28 is the endless belt 29. The generator 10 28 is connected to the two coils of the electro-magnet respectively by the lead wires 30 and 31. By this arrangement, when the generator is operating, the plates 17 and 18 in the bottom of the chute will be magnetized and will 15 establish such a zone of electrical influence that any metallic objects passing down the chute with the grain will be drawn to and held upon the plates. Mounted on the landing 10 is the incandescent light bulb 32, electrically connected to the two lead wires 30 and 31 respectively by the lead wires 33 and 34, as shown in Fig. 1. The purpose of this lamp is to act as a signal to the operator and inform him if the generator and the electro-magnet is working or not working. Below the 20 plates 17 and 18 and in the bottom of the chute is the trap door 35 hinged at its lower end. Secured to its free end are two metal bars 36 capable of engaging a projection 37 integrally 25 formed on each of the plates 17 and 18 respectively. This arrangement not only limits the trap door from passing beyond the closed position, but when the electro-magnet is functioning the door will be held in closed 30 position by the magnetic attraction, as shown in Fig. 1 and Fig. 2. However, if the generator fails or the mill should cease to operate, the plates 17 and 18 will release the door and it will fall to an open position as shown in 35 the dotted lines in Fig. 1, thereby providing an opening in the bottom of the chute through which will fall any metallic objects that might have been held on the plates 17 and 18 and released by the failing of the electro-magnet. This automatic feature prevents all 40 the metal objects that might have been on the plates from passing directly into the mill in mass, which would be more damaging than if no magnetic separator were used and the 45 metal fragments could have passed into the mill one at a time. Another advantage of this automatic feature is experienced when it is desired to remove metallic accumulations on the plates. All that is necessary is to shut 50 off the mill or generator and the door will fall open and allow the objects to fall into the container or vessel 38 placed in such a position as to receive them. This eliminates the necessity of manually pulling the captured 55 metallic objects from the plates with insulated pliers before the mill is shut down. I have designated the tramp iron or captured metallic objects by the numeral 39. Once the door is in open position, it is of course, necessary to move it near a closed position in order 60 65

that the plates 17 and 18 may exert magnetic attraction on the bars 36 and draw and hold the door in a closed position. To facilitate the manual closing of the door 35 from the landing 10, I have provided the rope 40 70 having one of its ends secured to the trap door and its other end passing through a hole in the floor 10 and secured to the handle member 41.

If a very large chute for transporting the 75 grain or other non-magnetic material is used, more than one magnet may be installed, or if desired, a magnet having three poles may be used.

Although in my drawings and description 80 I have shown a magnet artificially influenced by a direct current from a generator, it is to be understood however, that other currents and various types of magnets may be employed.

Some changes may be made in the construction and arrangement of my improved magnetic separators without departing from the real spirit and purpose of my invention and it is my intention to cover by my claims 90 any modified forms of structure or use of mechanical equivalents which may be reasonably included within their scope.

I claim:

1. In a device of the class described, an 95 inclined chute for transporting non-magnetic material, a trap door in the bottom of said chute, a metal bar secured to said door, a plate secured in said chute and capable of engaging said bar when said door is in a closed 100 position, and a magnet making contact with said plate, for holding said trap door in a closed position when said metal bar is in contact with said plate, and the retaining and holding of magnetic matter passing down 105 said chute on said plate.

2. In a device of the class described, an inclined chute for transporting non-magnetic material, a door in the bottom of said chute, hinges for securing said door at its lower end 110 to said chute, a metal bar secured to the opposite end of said door, a metal plate secured to the bottom of said chute and capable of making contact with said bar when said door is in closed position, and a magnet making 115 contact with said plate for holding said door in a closed position when said bar is in contact with said plate, and the retaining and holding of magnetic matter passing down 120 said chute on said plate when said magnet is functioning.

3. In a device of the class described, an inclined chute for transporting non-magnetic material, a hinged door in the bottom of said chute, a metal bar secured to said door, a 125 metal plate in the bottom of said chute and capable of making contact with said bar when said door is in a closed position, an electro-magnet making contact with said plate for holding said door in a closed position when 130

- said bar is in contact with said plate, and the retaining and holding of magnetic matter passing down said chute on said plate when said electro-magnet is functioning, and a 5 means for manually bringing said bar in contact with said plate at a distance from said door.
4. In a device of the class described, a chute for transporting non-magnetic material, a 10 plate in the bottom of said chute, an electro-magnet making contact with said plate, said chute having an opening in its bottom below said plate, a door in said opening, a metal bar secured to said door, and a projection formed 15 on said plate and designed to extend over said bar when said door is in a closed position for holding the same in that position by magnetic force when said electro-magnet is operating.
- 20 5. In a device of the class described, a chute for transporting non-magnetic material, said chute having an opening in its bottom, two metal plates in the bottom of said chute, a projection formed on each of said plates and 25 extending over said opening, a hinged door in said opening, two metal bars each capable of engaging the two projections respectively, and an electro-magnet having its two poles making contact with said two plates respectively for holding said door in a closed position when said metal bars are engaging two projections, and the attracting and holding of magnetic material on said plates that is passing through said chute.
6. In a device of the class described, an inclined chute for transporting non-magnetic material, two plates secured in the bottom of said chute, a trap door in the bottom of said chute, metal bars secured to said door capable of engaging said plates when said 30 door is in closed position, a metal U-shaped member in electrical contact with said two plates, a coil of wire around each fork of said U-shaped member, and designed to lead to a generator thereby so magnetizing said plates 35 that said door will be held in a closed position and magnetic matter passing down said inclined chute will be retained and held on said plates as long as said generator is operating.

ARCHIE BURNS.
